UNITED STATES PATENT OFFICE.

HARRY W. PILLATOS, OF SPOKANE, WASHINGTON, ASSIGNOR OF ONE-HALF TO GUS KREKALES AND ONE-HALF TO JOSEPH W. WEIN, BOTH OF SPOKANE, WASHINGTON.

SWITCH LOCK.

Application filed December 30, 1925. Serial No. 78,348.

My present invention relates to an improved switch lock for use in connection with railway switches, and designed as a safety appliance for co-operation with the switch points of the standard type of switches, which switch points are connected and move laterally for opening and closing the switch. The switch lock is manually operated independently of the switch-throwing mechanism and is operated both before and after each throw of the switch.

The switch-lock contemplates the utilization of a pair of connected locking members or blocks, longitudinally slideable with relation to the railway tracks or rails for co-action with the two switch points, to hold said points in adjusted position. As is well known the standard type of manually operated switch-throwing mechanism, and particularly the connecting rod or tie rod of such mechanism, is subject to breakage, and under such conditions one or the other of the two switch points is thus free to be spread open by passing wheels resulting in accidents. The primary object of my invention is the provision of a safety device or lock for use with the switch tongues that will hold them at all times in adjusted position, whether the switch is open or closed, against accidental displacement.

The invention consists in certain novel combinations and arrangements of parts as will hereinafter be more fully set forth and claimed.

In the accompanying drawings I have illustrated one complete example of the physical embodiment of my invention wherein the parts are combined and arranged in accordance with the best mode I have thus far devised for the practical application of the principles of my invention.

Figure 1 is a perspective view showing in detail one of the switch-point locks.

Figure 2 is a plan view showing a standard type of switch with the lock of my invention applied thereto.

Figure 3 is a detail sectional view through a rail and switch-rail showing the relation of a lock-block to these rails.

In order that the general arrangement and relation of parts may readily be understood I have shown in Figure 2 a portion of a railway including the ties 1, railway rails 2, 2 and switch rails 3 and 4 laterally movable with relation to the track rails,

A well known type of manually operated, rotary switch throwing mechanism includes the tie rod 5 between the switch rails, the connecting rod 6, which is connected to the switch stand 7 by crank arm 8, and the operating lever 9 by means of which the switch rails are moved laterally in usual manner.

In connection with the points of the switch rails I utilize the locking mechanism which is intended, except when the switch is actually being thrown, to be at all times in locking position with relation to the switch points, for the purpose of rigidly holding the switch rails in proper position against displacement.

The locking mechanism includes a pair of heavy, solid, lock blocks 10 and 11, each of which is fashioned with three wedge shaped tongues 12 which form between them a pair of grooves or recesses 13 and 13' that are complementary to the points of the switch rails 3 and 4.

One of these lock blocks is used at the inner side and contiguous to each track rail and provided with a lower guide flange 14 at its inner side. The rail plate 15 on which the track rail rests and upon which the switch point is movable is fashioned with a Z-bar 16 which may be bolted thereto as shown.

The pair of lock blocks are thus disposed on the rail plates and retained between the track rail at their outer sides and the Z-bar at their inner sides in order that they may be slid back and forth parallel with the track rails. In normal locked position the blocks engage the rail points or switch points as shown in Figure 2 with the points of the switch rails fitting snugly into the wedge shaped recesses. The tops of the lock blocks, as seen in Figure 3, are below the ball of the track rail and below the top of the switch rail point, to permit passage of the flanges of the wheels of rolling stock, but the recessed lock blocks or slide bolts 10 and 11 engage the switch points over an area sufficient to insure a rigid retention of the points. Thus the properly spaced switch points are at all times maintained in that position whether the switch is open or closed.

The two slide bolts or lock blocks 10 and 11 are joined by a tie rod 17 rigidly secured to each slide bolt and the slide bolts are

slid with a simultaneous movement out of and into engagement with the switch points by actuating the operating lever 18 which is pivoted at one side of the railway track 5 adjacent to the switch operating mechanism for convenience of the trainman or switch man. The pivoted lever 18 is connected to a link 19 and rock shaft 20 journaled in bearings 21 secured to one of the ties and extending under one of the track rails to approximately the center of the track where it is connected by a crank arm 22 thereon and a link 23 to the tie rod 17 of the slide bolts.

In Figure 2 by dotted lines the lock is 15 shown in open position and it will be apparent that by turning the lever 18 to the dotted position at the right the slide bolts are withdrawn from the switch points in order that the switch throwing mechanism may be operated to throw the switch. After the 20 switch is thrown the lever 18 is turned from dotted position to full line position to cause engagement with the switch points of another pair of notches or recesses of the slide 25 bolts. It will be understood that the slide bolts are movable longitudinally only, while the switch points are of course movable laterally of the track rails, and therefore the switch points are engaged by a selective 30 or alternate pair of notches or recesses of the slide bolts depending upon the position of the switch points.

Having thus fully described my invention,

what I claim as new and desire to secure by Letters Patent is—

1. The combination with a pair of laterally movable switch points and track rails, of a pair of longitudinally movable slide bolts guided, at the outer sides by said track rails and provided with guides at their inner sides, said slide bolts each having a pair of recesses for alternate engagement with said points, and means for simultaneously actuating said bolts. 40

2. The combination with a pair of longitudinally slidable lock-bolts each having a pair of spaced recesses for alternate engagement with switch points, of means for supporting and guiding said bolts, a tie rod between the bolts, and lever operated mechanism for actuating said bolts. 45

3. The combination with a pair of laterally movable switch rails and track rails and tie plates secured beneath the rails, of a pair of slide bolts having pairs of recesses 55 for alternate engagement with said switch rails, said bolts guided at one side by the track rails, guide flanges at the inner sides of said bolts and guide devices for co-action therewith on said tie plates, a tie rod connecting said bolts and lever operated mechanism for actuating said bolts. 60

In testimony whereof I affix my signature.

HARRY W. PILLATOS.

slid with a simultaneous movement out of and into engagement with the switch points by actuating the operating lever 18 which is pivoted at one side of the railway track 5 adjacent to the switch operating mechanism for convenience of the trainman or switch man. The pivoted lever 18 is connected to a link 19 and rock shaft 20 journaled in bearings 21 secured to one of the ties and 10 tending under one of the track rails to approximately the center of the track where it is connected by a crank arm 22 thereon and a link 23 to the tie rod 17 of the slide bolts.

In Figure 2 by dotted lines the lock is 15 shown in open position and it will be apparent that by turning the lever 18 to the dotted position at the right the slide bolts are withdrawn from the switch points in order that the switch throwing mechanism may be operated to throw the switch. After the 20 switch is thrown the lever 18 is turned from dotted position to full line position to cause engagement with the switch points of another pair of notches or recesses of the slide 25 bolts. It will be understood that the slide bolts are movable longitudinally only, while the switch points are of course movable laterally of the track rails, and therefore the switch points are engaged by a selective 30 or alternate pair of notches or recesses of the slide bolts depending upon the position of the switch points.

Having thus fully described my invention,

what I claim as new and desire to secure by Letters Patent is—

35

1. The combination with a pair of laterally movable switch points and track rails, of a pair of longitudinally movable slide bolts guided, at the outer sides by said track rails and provided with guides at their inner 40 sides, said slide bolts each having a pair of recesses for alternate engagement with said points, and means for simultaneously actuating said bolts.

2. The combination with a pair of longitudinally slideable lock-bolts each having a pair of spaced recesses for alternate engagement with switch points, of means for supporting and guiding said bolts, a tie rod between the bolts, and lever operated mech- 50

45

anism for actuating said bolts.

3. The combination with a pair of laterally movable switch rails and track rails and tie plates secured beneath the rails, of a pair of slide bolts having pairs of recesses 55 for alternate engagement with said switch rails, said bolts guided at one side by the track rails, guide flanges at the inner sides of said bolts and guide devices for co-action therewith on said tie plates, a tie rod connecting said bolts and lever operated mechanism for actuating said bolts.

60

In testimony whereof I affix my signature.

HARRY W. PILLATOS.

Certificate of Correction.

It is hereby certified that Letters Patent No. 1,596,510, granted August 17, 1926, upon the application of Harry W. Pillatos, of Spokane, Washington, for an improvement in "Switch Locks," were erroneously issued to "Gus Krekales" and "Joseph W. Wein" as assignees of one-half each of said invention, whereas said Letters Patent should have been issued to the inventor, said *Pillatos, one-half to Gus Krekales, and one-fourth to Joseph W. Wein, both of Spokane, Washington*, as shown by the records of assignments in this office; and that the said Letters Patent should be read with this correction therein that the same may conform to the record of the case in the Patent Office.

Signed and sealed this 19th day of October, A. D. 1926.

[SEAL.]

WM. A. KINNAN,
Acting Commissioner of Patents.
